UNITED STATES PATENT OFFICE.

WILLIAM S. DAVIDSON, DECEASED, BY ANNA L. NEAL, ADMINISTRATRIX, OF
PHILADELPHIA, TENNESSEE.

RAILWAY MAIL CRANE.

1,414,690.

Specification of Letters Patent. Patented May 2, 1922.

Application filed June 10, 1919. Serial No. 303,231.

To all whom it may concern:

Be it known that I, ANNA L. NEAL, a citizen of the United States, residing in the city of Philadelphia, in the county of Loudon 5 and State of Tennessee, being administratrix of the estate of WILLIAM S. DAVIDSON, deceased, who invented certain new and useful Improvements in Railway Mail Cranes, do hereby declare that the following is a 10 full, clear, and exact description of the same.

This invention relates to improvements in railway mail cranes and particularly to the type of mail crane forming the subject matter 15 of Letters Patent of the United States No. 1,192,872, issued to William S. Davidson on August 1st, 1916.

The purpose of this invention is to simplify and perfect certain details of construction in the said patented crane, one object 20 being to house the flexible overhead pouch support in the hollow standard or mast of the crane.

A further object is to utilize a chain in the 25 mast as a counterweight for retracting the overhead flexible pouch support to safety position after the pouch has been delivered.

A further object is to mount the mast or tubular standard in a cast base anchored in 30 or to a concrete foundation and provided with an opening giving access to a chain fastening by means of which the chain in the mast may be secured in the desired pouch supporting position.

35 A further object of this invention is to utilize a horizontally swinging safety rod as a means for controlling the movements of the tie chain or flexible connection which is attached to the bottom of the mail pouch, 40 this safety rod being pivotally mounted on a bracket on the mast which preferably serves both as an anchorage for the guy chain and as a support for a lantern.

The invention also comprises various 45 details of construction and arrangements of parts, which in their preferred embodiment only are illustrated in the accompanying drawings, and in which:

50 Fig. 1 illustrates the apparatus in elevation supporting a mail pouch in position to be delivered to the train.

Fig. 2 is a detail view of the bracket for the safety rod.

Similar reference numerals refer to similar parts throughout the drawings.

As illustrated, my improved crane comprises a mast 1 formed of pipe or a like tubular body which at its lower end is securely clamped in the split upper end 2 of the base 3, this split upper end being provided with 5 pairs of clamp lugs 4 through which bolts 5 are passed, and when tightened serve to rigidly clamp the mast in position in the base. The base itself is mounted on a concrete foundation 6 and is securely attached thereto by anchor bolts 7. The base is cast with an elongated bottom flange 8 projecting a substantial distance from the base on its side opposite the track 9. The side of the base towards the track is cast with an opening 10 formed to give access to a chamber therein in which a pulley chain 11 or equivalent flexible element is exposed and at its lower end is made fast to an anchor bolt 12 secured in the foundation 6. The chain is passed upwardly through the mast and over a pulley 13 journaled on a pin 14 in a top tubular arm 15 formed by a casting which is adapted to close the top of the mast and to be clamped thereto by bolts 16 passing through clamping lugs or ears 17. The chain after passing over the pulley 13 continues through the tubular arm and about a pulley 18 journaled in the outer end of the arm and thence passes downwardly through 80 an opening 19. This opening 19 is elongated at right angles to the track. At its free or delivery end the chain carries a spring link 20 and immediately above this spring link is connected to a guy chain 21 85 made fast at its other end to a bolt 22 which connects at one side the clamp members 23 and 24 which form the bracket which supports the signal lamp 25 on one side and the safety rod 26 on the other side. This rod 26 90 extends towards the track and is provided at its free end with an elongated slot 27 which is connected to the spring link 20 at the top of the tie chain 28, which chain at its lower end is made fast to a cross tie 29 95 or other suitable anchorage. To each of the spring links 20 is connected a pouch spring 100

30 formed by a spring loop, the spread ends of which are adapted to be passed through rings 31 at the top and bottom of the mail pouch 32. The mast also carries above the 5 lamp bracket a guy hook 33 suitably clamped or made fast to the mast and over which the guy chain 21 works. The clamp member 23 towards the track is rounded at 34 to provide a suitable attachment for the safety rod 10 26 which has an enlarged eye 35 adapted to slip over the clamp member and which will permit the rod to swing freely horizontally when the bracket members are clamped to the mast.

15 Within the upper portion of the open chamber in the base 3 I provide a slotted plate or web forming a chain fastener 36, this being preferably cast integral with the base and having the slot just large enough 20 to receive a link of the chain when inserted edgewise therethrough and to engage the under link so as to fasten the chain therein while leaving it free to be drawn outwardly and disengaged by the operator.

25 Having set up the apparatus in the manner described the chain 11 is released from its fastener 36 and is drawn down by the guy chain until the upper pouch spring is in convenient reach so that it may be inserted in 30 the upper ring of the pouch. The lower pouch spring is then raised and passed through the lower pouch ring 31 and the chain is drawn downwardly through the mast until the pouch is supported in the 35 manner shown, whereupon the chain is made secure in the fastener 36 and the apparatus is ready to deliver the pouch to the passing train. Immediately after the pouch has been detached from its fastenings, the 40 weight of the chain in the mast, being sufficiently greater than that hanging from the top of the mast, will immediately act as a counterweight to draw the free end of chain 11 and the guy chain 21 to the dotted line 45 position shown in Fig. 1, and at the same time the safety rod 26 and the tie chain 28 will fall away downwardly to a safe position. The arrangement of the chain in the tubular mast and the utilization of the chain 50 as a counterweight are important features in the durability and simplicity of the apparatus.

This invention is not intended to be restricted in scope to the specific embodiments 55 shown, but contemplates such modifications as come within the spirit and scope of the claims.

Having thus described my invention, what I claim as new and desire to secure by 60 Letters Patent, is:—

1. The combination, in a device for delivering articles to a moving train, of a hollow mast carrying an overhung arm and sheaves at its upper end and having a hollow base,

means to clamp the mast to the base which 65 will permit the mast under abnormal thrust strains on the arm to turn about a vertical axis in said base, a flexible member which extends upwardly through said mast and over said sheaves with its free end suspended 70 from said arm, means to anchor the end of the flexible member that is disposed within the mast, means on the free end of said flexible member adapted to releasably support the articles to be delivered, and a releasable 75 bottom fastening means for said article.

2. In a device for delivering articles to a moving train, a hollow cast base having a side opening, means to anchor said base, a mast formed by a pipe clamped in the top 80 of said base and having a tubular top arm, a chain which works through said arm with one portion hanging downwardly through said pipe, means to anchor the lower end of said chain portion in position to be accessible 85 through the opening in said base, means carried by the other end of the chain for releasably supporting the article to be delivered, a releasable bottom fastening 90 means for said article, and chain fastening means in the base for holding the chain in position to support the article at the desired elevation.

3. The combination, in a railway mail crane, of a cast metal hollow base open at 95 one side and through the top and provided with pipe clamping means, a pipe clamped in the top of the base and forming a mast for the crane, a tubular arm mounted on the top of the mast, and means to clamp said arm to the mast, sheaves in said arm, a pulley chain anchored near the bottom of the base and passing freely upwardly through the mast and over said sheaves in the tubular arm, a releasable mail pouch supporting 100 means carried by the free end of the chain, a guy chain connecting said latter end of the pulley chain to the mast, a tie chain having suitable anchorage means for its 105 lower end and releasable pouch engaging means at its upper end, a safety rod connected to the upper end of the tie chain, means to swivelly connect said rod to the mast, and a slotted plate in the base forming 110 a chain fastener disposed above the anchorage means in the pulley chain, substantially as described.

4. In a railway mail crane, a foundation, a hollow casting anchored on said foundation and having an open chamber for a counterweight and yieldable clamp jaws at its upper end, a vertical mast having its lower end mounted in said clamp jaws at the top of the base, an overhung arm at the top of the mast, a flexible connection having the 115 counterweight element mounted in said base, said connection being passed up through the pipe and having its free end suspended from

said arm, means on the free end of said connection to detachably support a mail bag, means to releasably hold the lower end of a mail bag when suspended from said connection, and means in the hollow base to engage said connection and support the bag at the desired elevation.

In testimony whereof, I affix my signature.

ANNA L. NEAL,
*Administratrix of the estate of W. S. David-
son, deceased.*
